UNITED STATES PATENT OFFICE.

JOHN D. BYER, OF BUTTE, MONTANA.

MATCH-DISPENSER.

1,289,112.

Specification of Letters Patent.

Patented Dec. 31, 1918.

Application filed March 21, 1917. Serial No. 156,329.

To all whom it may concern:

Be it known that I, JOHN D. BYER, a citizen of the United States, residing at Butte, county of Silverbow, and State of Montana, 5 have invented certain new and useful Improvements in Match-Dispensers, of which the following is a specification.

My invention has for its object the provision of a match dispenser which will be an 10 improvement on the match dispenser set forth in my Patent No. 1199244, dated September 26, 1916.

A further object is to provide a dispensing device for matches, tooth picks or similar 15 articles having a cup or receptacle and hinged match or tooth pick holding top sections adapted to grasp the match or tooth pick and hold it in convenient position for removal by the user. In that respect, the invention is an improvement on the top sections 20 of my aforesaid patent as the article is retained, rather than delivered, when elevated by the slide; furthermore, the construction is simplified and rendered cheaper 25 to manufacture, more reliable in operation, and the match or tooth pick is held in more accessible position.

Another object of the invention is the provision of an operating lever, a dispensing slide, and an improved operative connection 30 between the lever and the slide whereby the action is positive and regular and there is little likelihood of parts getting out of order. This part of the invention is greatly 35 simplified over the operating connections between the lever and the slide of the device of my patent aforesaid.

A further object is to generally improve, 40 simplify, and cheapen the construction of a match or tooth pick dispenser and to render it reliable in action even when operated improperly or at an excessive speed.

The embodiment of the invention herein-after set forth is to be considered as illustrative, rather than restrictive, of the scope 45 thereof, as certain modifications may be resorted to without departing from the principles of the improvements embodied therein.

In the accompanying drawings:-

50 Figure 1 is a rear elevation, a part of the casing being removed to show the dispensing slide and the operating connection;

Fig. 2 a vertical section on line 2—2 Fig. 1;

55 Fig. 3 a view like Fig. 1, but showing the lever depressed and the dispensing slide raised to deliver a match or tooth pick; and

Fig. 4 a detail view showing the manner in which the slide delivers the article to the hinged top sections and how they hold the article.

60

The base 1 may be of any form and is preferably provided with a match scratcher 2 if the device is used for dispensing matches. Rising from the base 1 are the ends 3 which may be secured to the base by angle pieces 4. 65 At their upper parts the end pieces 3 have circular heads 5 constituting the ends of the match or tooth pick, cup or receptacle 6. Removal plates 7 connect the end pieces 3 below the heads 5.

70

The cup or receptacle is of general cylindrical form, the lower part comprising arc-shaped sections 8 having inspection slots 9, the parts 8 being connected to the ends 5. The slots 9 permit inspection of the articles, 75 such as matches or tooth picks 10, contained within the cup or receptacle 6 so that the supply may be replenished, when necessary. Furthermore, any implement may be inserted in the slots 9 to readjust the articles 80 10 should they become crossed or clogged. The upper portion of the receptacle 6 is substantially covered by arc-shaped top sections 11 which are substantial duplicates. Each section 11 is hinged at 12 to the heads 5 in 85 substantial alinement with its lower edge 13. A rod or pin 14 may extend lengthwise through the lower portion of the section 11, in each instance, for this purpose, the ends being loosely received at 12 in the heads 5. 90 A coil spring 15 surrounds the central portion of the rod 14 and has its ends 16, 17, bearing on the section 11 and the section 8, respectively. The spring holds the section 11 closed. To limit the extent of closing of 95 the sections 11, there are provided thereon lugs 18 which enter notches 19 in the edges of the heads 5, but normally the lugs 18 do not bear on the bottoms of the notches 19 and, consequently, the jaws 20 which are 100 provided on the sections 11, bear against each other. The jaws 20 are provided with one or more grooves or serrations 21 on their inner faces to enable them to frictionally hold one or more matches or tooth picks. 105

The jaws 20 are spaced a suitable distance apart as shown in Figs. 1 and 3 and between them there is a large space 22 comprising cutout portions in the upper edges of the sections 11 of sufficient size to enable the 110 user to insert the thumb and forefinger on opposite sides of the match or tooth pick to

easily grasp the same. Other cutout portions 23 are provided to allow the dispensing slide to be elevated to the height necessary to deliver the match or tooth pick shown at 24, Fig. 4, to the jaws 20.

The dispensing slide 25 operates within the casing comprising the ends 3 and the plates 7 and has its edges slideable in groove 26 on the inner faces of the said ends and heads. The slide is provided with a plurality of projections 27 on its upper edge, all of which have a groove 28 of a size suitable to receive a single match or tooth pick. Preferably there are three of the projections 27, the end sections being adapted to pass into the openings 23 when the slide is elevated and the center one passing into the opening 22, the spaces 30 being in line with the jaws 20 so that those portions of the tooth pick or match bridging the spaces 30 are free for presentation to the jaws 20. Consequently, the match or tooth pick 24 is offered to the jaws and they immediately grasp it as shown in Fig. 4.

25 The operating lever 31 is pivoted at 32 to one of the plates 7 and is retracted by a spring 33 coiled around said pivot and co-operating with the lever at 34 and with an end piece 3 at 35. In the lower portion of 30 the slide there is a slot 36 which has a straight lower edge 37, a cam edge 38 and a dwell 39. A pin 40 on the lever 31, projects into the slot 36. The direct operating connection thus provided between the lever 35 and the slide, is positive in its action and practically impossible of getting out of operative condition. When the slide is in its raised position and when it is in its lowered position, the pin lies in the dwell 39 and 40 consequently there is no lost motion at those times nor any possibility of further upward or downward movement. The cam 38, however, provides for the elevation of the slide when the lever is depressed and the size of 45 the space 36 enables the slide to be drawn downwardly by a snap like action when the lever is released, this being due to the gravity of the slide and the action of the spring 33.

50 The lever 31 has its handle portion oper-

ating in a slot in one of the end pieces 3 and provided with a stop 41 which is adapted to bear against the side piece 3 to arrest the retraction of the lever and the slide, as shown in Fig. 1.

I am aware that it is unnecessary to form the sections 11 of arc shape and to employ the exact arrangement of the projections 27; furthermore, that there are other details of construction which might be modified without departing from the principles of the invention.

Having thus described my invention, what I claim as new and desire to secure by Letters Patent is:—

1. In a dispenser for matches or the like, the combination with a receptacle whose top has a movable, automatically closing section, said top and section thereof being provided with jaws for jointly holding the match or the like in position for sidewise removal by the user, of a dispensing slide adapted to move the match or the like sidewise from the receptacle and deliver it, in that position, to said jaws.

2. In a dispenser for matches or the like, the combination with a receptacle whose top is formed of sections having means adapted to jointly hold the match or the like in position for sidewise removal by the user, one of said sections being movable in relation to the other section and adapted to automatically close, of a dispensing slide adapted to move the match or the like sidewise from the receptacle and deliver it, in that position, to said holding means of said top sections.

3. In a dispenser for matches or the like, the combination with a receptacle having its top formed of relatively movable, spring-closed sections each having a pair of jaws arranged and adapted to jointly hold the match or the like in position for sidewise removal by the user, of a dispensing slide adapted to move the match or the like sidewise from the receptacle and deliver it, in that position, to said jaws.

In testimony whereof, I hereunto affix my signature.

JOHN D. BYER.
